UNITED STATES PATENT OFFICE.

WALTER DUKE SMITHEY, OF BAY CITY, TEXAS.

EX-1

TURBINE-MOTOR.

1,257,140.

Specification of Letters Patent. Patented Feb. 19, 1918.

Application filed August 22, 1917. Serial No. 187,583.

To all whom it may concern:

Be it known that I, WALTER D. SMITHEY, a citizen of the United States of America, residing at Bay City, in the county of Matagorda and State of Texas, have invented certain new and useful Improvements in Turbine-Motors, of which the following is a specification.

This invention relates to turbine motors, and means for controlling same.

The object of the invention is to provide a simple and economical motor which can be effectively operated by motive fluid.

A further object of the invention is to provide improved means for governing the speed of the turbine motor.

The invention also comprehends improvements in the details of construction and arrangement of parts which will be hereinafter described, and particularly pointed out in the claims.

In the drawings:

Figure 1 is a perspective view of my improved motor,

Fig. 2 is a central vertical section;

Fig. 3 is a detail view of the resilient duct,

Fig. 4 is a transverse section of the motor.

1 indicates a motor casing formed with an inlet port 2, and an outlet port 3, the latter communicating with a muffler 3^a. Between the inlet port 2 and outlet port 3, is bolted at 4, a resilient element having an inlet duct 5, which is formed at its exit end with a concave shield 6. Secured to a driving shaft 7, within the casing 1 is a rotor 8, formed on its periphery with a plurality of pockets 9. The shield 6 snugly fits the periphery of the rotor and forms a tight joint to prevent the motive fluid leaking from the pockets.

40 The rotor travels in oil contained in the casing, and the bottom of the latter is formed by a detachable plate 11, which inclines downwardly toward the rotor to form a well directly under the latter.

45 The casing 1 is provided with a hollow extension 12, which communicates with the inlet port 2. 13 indicates a valve seat formed in the extension 12, to one side of the inlet port 2, and coöperating with this seat is a valve 14, the stem 15 of which extends up through the top of the extension, and is provided with an adjustable nut 16.

50 The driving shaft 7, extends through an opening 17, in one side of the casing 1, and which communicates with a chamber 18,

formed by an auxiliary casing 19, bolted or otherwise fastened to one side of said casing. Bolted to the auxiliary casing 19, is a cap plate 20, in which is formed a central bearing 21, for one end of the driving shaft 7, and between the end of the latter and the cap plate is interposed a strong cup shape thrust spring 22. This thrust spring forces the shaft 7 laterally which retains a flanged washer 23, snugly against the bearing 24, in the opposite side of the casing.

The auxiliary casing contains oil to lubricate the parts to be described, and the thrust spring and washer serve as a means for preventing the oil leaking around the bearing.

Slidably mounted on the shaft 7 by a key and slot connection 25, is a cone 26, located in the opening 17, and provided with ears 27, to which links 28 are pivoted. The opposite ends of the links are pivoted to weights 29, which in turn are pivoted to ears 30, on a collar 31, fixed to the shaft 7.

32, indicates a vertical slidable lever mounted in a guide in the casing 1, and pivoted at its upper end to a controlling lever 33, formed with an opening 34, in which loosely fits the nut 16 on the valve stem 15. Pivoted to a standard on the extension of the casing is a handle 35, the foot end 36, thereof engaging under the free end of the controlling lever 33, as shown. A spring 36^a, is attached to the controlling lever 33 and a screw 37 on the extension which serves to normally draw the controlling lever down and thereby open the valve, and which also acts to draw the slidable lever down and detain its beveled end 40 in contact with the surface of the cone.

A coupling 41, is screwed to the outer end of the extension of the casing, and in this coupling is mounted a pressure regulating valve.

In operation the handle 35, is released, which causes the spring 36, to open the valve 14, and the motive fluid passes through the inlet port 2, inlet duct 5, to the pockets on the periphery of the rotor. The shield 6, acts as a packing, consequently the full effective force of the motive fluid acts on the pockets to rotate the rotor.

As the rotor travels at a rapid rate in a bath of oil, it follows that the bearings, between the shield and the peripheral surface of the rotor, and the shaft bearings will be thoroughly lubricated.

105

110

As the speed of the rotor increases beyond that set by the tension of the spring 36, the weights 28, are centrifugally thrown outwardly which slides the cone 25, on the shaft 7, and elevates the vertical lever 32, which raises the controlling lever 33 against the tension of the spring 36, and correspondingly raises the valve 14, to its seat 13, and shuts off the supply of motive fluid. Immediately the speed of the rotor decreases, the spring 36, acts to restore the lever valve, and the weights act to restore the cone.

Located in the extension of the casing is an adjusting screw 70, which bears on the resilient element to regulate the position of the shield 6 on the periphery of the rotor. The purpose of this adjustment is to provide means for taking up wear. Then again if high pressure motive fluid is used, and the resilient element was set for low pressure, leakage would follow if no means was provided to adjust the shield. The adjustment when made is set by a nut 71.

What I claim is:

1. In a motor, the combination with an elongated casing provided at one end near the top with an exit port and at its rear with an inlet port which extends through the top wall, a rotor mounted in the casing, said rotor having a plurality of peripheral pockets, a resilient horizontally disposed member rigidly fixed at one end to the inner surface of the top wall of the casing, the opposite end of the resilient member having an integral shield which engages the periphery of the rotor, the resilient member being formed with a passage which at one end communicates with the inlet port and which extends through the shield to communicate with the pockets when the rotor revolves, and a screw extending through the casing and engaging the resilient member adjacent the shield to adjust the position of the latter on the periphery of the rotor, the outer end of the shield terminating adjacent the outlet port.

2. In a motor, the combination of an elongated casing provided at its upper rear end with an exit port and at its front upper end with an inlet port, a rotor mounted in the casing, said rotor having a plurality of peripheral pockets, an elongated flat resilient member formed at its rear end with a shield and disposed against the inner surface of the top wall of the casing and formed with a passage extending through the shield and toward the forward end to a point in the top of said member, forward end of the passage registering with the inlet port in the casing, an adjusting screw extending through the casing and engaging the top of the resilient member to adjust the position of the shield on the periphery of the rotor.

3. In a motor, the combination of an elongated casing having an inclined bottom, the casing containing a bath of oil in which a rotor runs, a rotor mounted in the rear portion of the casing, said rotor having a plurality of peripheral pockets, the casing having an exit port in the top wall at the rear end and an inlet port in the top wall near the forward end, a resilient member fitted to the inner surface of the top wall of the casing and formed with a passage which extends through the top of said member and registers with the inlet port, the rear end of the passage communicating with the pockets in the rotor when the latter is rotated, and means on the casing for adjusting the position of the resilient member on the periphery of the rotor, the rear end of the resilient member terminating adjacent the exit port to permit escape of the motive fluid from the casing.

4. In a motor, the combination of an elongated casing provided with a lateral extension which is in communication with the casing, the casing and the extension containing a bath of oil, the casing having an inlet port at one end and an exit port at its upper end, aligned bearings formed in the casing and the end wall of the lateral extension, a shaft mounted in the bearing, a rotor mounted on the shaft and rotatable in the casing, said rotor having a plurality of peripheral pockets, a resilient elongated member fitted to the inner surface of the top wall of the casing and formed with a passage which extends therethrough and registers at one end with the inlet port, the rear end of the passage communicating with the pockets in the rotor when the latter is rotated, means on the casing for adjusting the position of the resilient member on the periphery of the rotor, the rear end of the resilient member terminating adjacent the exit port to permit the escape of the motive fluid from the casing, a valve for controlling the inlet port, an arm connected to the stem of the valve, a lever for actuating the arm, and means between the shaft and the opposite end of the arm to automatically actuate the valve.

5. In a motor, the combination of an elongated casing containing a bath of oil, in which a rotor runs, a rotor mounted near one end of the casing, said motor having a plurality of peripheral pockets, the casing having an exit port in the top wall at the rear end and an inlet port at the forward end, a resilient member fitted to the inner surface of the top wall of the casing and formed with a passage which extends therethrough and registers with the inlet port, the rear end of the resilient member having a curved shield to engage the periphery of the rotor, the passage in the resilient member

extending through the shield and communicating with the pockets in the rotor when the latter is rotated, means at the forward end of the resilient member for permanently securing the resilient member to the casing, and means on the casing for adjusting the position of the shield on the periphery of the rotor, the rear end of the resilient member

terminating adjacent the exit port to permit escape of the motive fluid from the passage. ¹⁰

In testimony whereof I affix my signature in the presence of two witnesses.

WALTER DUKE SMITHEY.
